(57) **CLAIM**

The ornamental design for a miniature compact driver tool, as shown and described.

DESCRIPTION

FIG. 1 is a perspective top, left side, front view of the miniature compact driver tool;

FIG. 2 is a perspective bottom, right side, rear view thereof;

FIG. 3 is a top plan view thereof;

FIG. 4 is a bottom plan view thereof;

FIG. 5 is a right side view thereof;

FIG. 6 is a left side view thereof;

FIG. 7 is a front view thereof;

FIG. 8 is a rear view thereof;

FIG. 9 is a perspective top, right side, rear view of the miniature compact driver tool with a component holding cover in a fully open position;

FIG. 10 is a bottom view thereof; and,

FIG. 11 is a rear view thereof.

The broken lines in the drawings illustrate features of the miniature compact driver tool that form no part of the claim.
